Patented Dec. 10, 1968

212,873

CAP FOR AN AEROSOL PACKAGE

William G. White, Wilmington, Del., assignor to E. I. du Pont de Nemours and Company, Wilmington, Del., a corporation of Delaware

Filed June 21, 1966, Ser. No. 2,756

Term of patent 14 years

(Cl. D9—258)

FIG. 1

FIG. 2

FIG. 3

FIG. 4

FIGURE 1 is a top plan view of a cap for an aerosol package showing my new design;

FIGURE 2 is a bottom plan view;

FIGURE 3 is a side elevational view; and

FIGURE 4 is a vertical sectional view taken along line 4—4 of FIGURE 1.

I claim:

The ornamental design for a cap for an aerosol package, substantially as shown.
